UNITED STATES PATENT OFFICE.

HERBERT WILFRED PERRY, OF TRICHINOPOLI, INDIA.

PERMANENT WAY-RAIL.

No. 857,199.

Specification of Letters Patent.

Patented June 18, 1907.

Application filed September 7, 1905. Serial No. 277,500.

To all whom it may concern:

Be it known that I, HERBERT WILFRED PERRY, a subject of the King of England, and a resident of Trichinopoli, India, have invented certain new and useful Improvements in Permanent Way-Rails, of which the following is a specification.

This invention has reference to permanent way rails, and more particularly to such rails as are provided with a renewable wearing surface or capping.

In the specification and drawing accompanying British Letters Patent No. 4,859 of 1900, granted to myself, is shown and described a permanent way rail having a renewable wearing surface or capping, the sides of the latter being turned inward to fit the head of the rail. This gave an unrollable section to the cap, and necessitated it being slid onto and off the rail from one end.

The object and effect of my present invention is to provide a renewable wearing surface or capping of a "rollable" section, of such contour that it may be fitted onto the head proper of the rail at any part of its length, the necessary grip or bite being obtained by making the curve or slope of the inner sides of the cap a little steeper, or more vertical, than the sides of the head of the rail, so that when pressed down by the weight of the wheels of an engine or other vehicle running over it, the cap settles down firmly and securely onto the head of the rail.

A drawing illustrating in section a rail, ac-

cording to my invention, accompanies this 35 specification.

Referring to this drawing, *a* generally designates the rail head, and *b* the renewable wearing surface or capping. As shown, the capping *b* may be rolled in course of manufacture, and in fitting to head *a* it is simply placed upon same, at any part of its length. The inner sides *b*¹ of the capping *b* are slightly steeper than the sides *a*¹ of the head *a*, for the purpose aforementioned.

If desired, the sides *b*¹, instead of being inclined outward, as shown, may be straight, and the slope of sides *a*¹ of head *a* varied slightly to correspond.

Having now described my invention, what 50 I claim as new, and desire to secure by Letters Patent is:—

A permanent way rail of the section illustrated, comprising in combination a rail head and a renewable and rollable capping, 55 the slope of the inner surfaces of the sides of said capping being a little steeper or more vertical than that of the sides of the head of the rail, whereby said capping is secured to the rail head solely by the bite or friction between the two.

In testimony whereof I have signed my name to this specification in the presence of two subscribing witnesses.

HERBERT WILFRED PERRY.
